IRON CORE FOR MAGNETIC APPARATUS

Application filed January 9, 1928, Serial No. 245,611, and in Germany September 14, 1926.

It is well known that in laminated iron cores for alternating current magnetization, with paper insulated punchings, the heat conductivity across the punchings is about one-hundredth part of the heat conductivity along the punchings. This ratio is even higher when thin punchings are used, such as, for instance, high frequency punchings. This can be easily understood because in the 10 direction across the punchings there is an insulating layer between the two punchings which is a poor conductor of heat.

It necessarily follows that the surface consisting of the exposed edges of the laminations would radiate heat many times faster, than any of the other surfaces that would consist merely of a flat side of one lamination referred to in this application as the flat surface of the core. For the purposes of 20 this invention such an exposed edge surface will be defined as the cross sectional cooling surface throughout this description and in the claim following.

According to this invention the conduction 25 of heat away from the core is improved by increasing the above defined cross sectional cooling surface to a multiple in respect to the flat surface by the simple expedient of making the extension of the cross sectional 30 surface of the laminations across the punchings a multiple of the extension along the punchings. This has the effect of increasing the very effective cross-sectional cooling surface relative to the ineffective flat surface, whereby the resulting cooling action of 35 the core is considerably increased over large surfaces of the core instead of over small surfaces of the core.

The invention is made clearer by the following detailed description taken with reference to the accompanying drawing in which

Figure 1 is a cross-sectional view of an improved form of iron core in accordance 45 with our invention.

Figure 2 is a cross-sectional view taken at right angles to Figure 1 through one of the core sections.

An especially suitable form of embodiment 50 according to the inventive idea is had by roll-

ing the sheet metal core material around a mandrel before cutting and then slicing this roll into thin sections. In this way, spirally wound laminated rings of small axial extension as compared to the radial extension or 55 discs are obtained, which can be placed in the transformer windings. In this manner too the cross sectional surface of the core is made a multiple of the flat surface which in this case is the outer cylindrical surface of the 60 rings. Fig. 1 shows discs or rings, R^1 , R^2 , etc., mounted on an insulating cylinder Z , through the center of which the transformer windings W are placed as shown. Fig. 2 is a cross section taken at right angles to the 65 section of Fig. 1. Fig. 2 also shows the spiral arrangement of the lamination in the cores R^1 to R^3 . This arrangement is quite suitable for high frequency transformers and permits the use of iron in high frequency trans- 70 mission circuits. Despite of the small over all dimensions of the high frequency transformer cores used in transmitters, it has been impossible to remove the generated heat which is proportionately no larger than with 75 usual apparatus. By the use of iron core in the described manner, the heat is removed by air blast instead of oil cooling so continuously that the iron will not assume any dangerous rise in temperature.

The cores shown in Figs. 1 and 2 possess the big advantage of increased cooling ability. This is especially important with iron cores that handle high frequency magnetization such as for frequency transformers iron-core choke modulators and the like, since, in this case, the use of iron leads very often to a condition where the losses in the form of heat cannot be carried away from the iron, even though the mean winding turn and the 80 copper losses related to it are small compared to the iron losses.

Having described our invention, what we believe to be new and desire to secure and protect by Letters Patent of the United 85 States:—

A core for high frequency electromagnetic apparatus comprising a group of core sections arranged in axial alignment, said sections being spaced from each other to pro- 100

vide passages for the free passage of a cooling medium between said sections, each of said sections consisting of a narrow strip of iron spirally wound to form a cylinder having a radial dimension which is a large multiple of the width of the strip, the width dimension of each of said strips being perpendicular to said passages whereby said passages intercept the paths of maximum conduction of heat developed in said core sections.

5
10 In testimony whereof we have affixed our signatures.

WALTER HAHNEMANN.
KARL SCHMIDT.
